UNITED STATES PATENT OFFICE.

WELLES M. POST, OF WILKINSBURG BOROUGH, PENNSYLVANIA.

DEVICE FOR SECURING BOND WIRES TO A RAIL-JOINT.

No. 891,860.

Specification of Letters Patent.

Patented June 30, 1908.

Application filed September 12, 1897. Serial No. 392,530.

To all whom it may concern:

Be it known that I, WELLES M. Post, a citizen of the United States, residing in the borough of Wilkinsburg, county of Allegheny, State of Pennsylvania, have invented a new and useful Device for Securing Bond-Wires to a Rail-Joint, of which the following is a specification.

The purpose of my invention is to support 10 rail bonds intermediate their points of attachment to the rails and to provide conductive contact at the points of support.

A further purpose of my invention is to protect the points of attachment of rail bonds 15 to the rails against undue strain.

A further purpose of my invention is to retain the bonding wires of rail bonds in taut 20 position across the fish plate and between points in proximity of the points of attachment with the rails.

It further consists of other novel features of construction, all as will be hereinafter fully set forth.

For the purpose of illustrating my invention, I have shown the forms thereof at present preferred by me, since these embodiments best illustrate the principle of the invention and give satisfactory and reliable results in practice, although it is to be understood that 25 the various instrumentalities of which my invention consists can be variously arranged and organized and that my invention is not limited to the precise arrangement and organization of these instrumentalities as herein shown.

Figure 1 represents in side elevation, one form of my invention. Fig. 2 represents the construction shown in Fig. 1 in transverse section upon line X—X. Fig. 3 represents a 40 transverse cross section similar to Fig. 2 but showing the support upon the opposite side of the rail. Fig. 4 represents in perspective, the form of support and contact shown in Figs. 1, 2 and 3. Figs. 5, 6, and 7 show in 45 perspective, modified forms of my support and contact piece.

Similar numerals of reference indicate corresponding parts in the figures.

Referring to the drawings:—In bonding 50 rails such as those shown at 1, it is customary to insert bonds 2 into the rails as at 3 and 4 upon side of the fish plate at the joint thereof, making use of the contact of the bond and rail at the point of insertion to establish electrical connection between the bond and rail

and to unite the rails electrically in this manner.

My invention is especially advantageous for use with a bond which is carried outside of the fish plate wherever it passes the same. 60 In my claims where I refer to the bond as exposed, I allude to the fact that it is through all or a portion of its length unprotected by the fish plate.

A relatively thin wire is often used for the 65 bond. My device as a support merely has greatest utility with their wires. As a means of improving contact it might be of equal utility with either thin or thick wires according to the requirements in individual cases. 70 Notwithstanding that various means are taken to insure tight metallic and electrical connection between the bond and the rail at the points 3 and 4, it is difficult to establish good electrical contact therethrough by reason of the small area of contact and the low 75 relative conductivity of the rail making contact with the bond. There is further difficulty in bonds of this character in that the bond necessarily sags somewhat if it be of at 80 all light construction and that for all sizes it is subject to mechanical interference from track hands and other sources causing it to sag further if it be thin or bulge with further liability to interference, accidental or intentional, and with consequent increased strain 85 upon the points of attachment to the rail, with the result that these points of attachment are loosened or broken and the electrical connection thereof impaired. 90

I secure the bonds to the fish plate by means of clips held in place preferably by the bolts which hold the fish plate in place and which clips may not only support the bonds against sagging or bulging or interference of any kind, but also increase the area 95 of electrical contact with the rail through the contact of the clips with the bonds, the contact of the bonds and clips with the fish plate and the contact between the fish plates 100 and the rails.

For the above named purposes I apply a clip 5, of which I have illustrated one form in Fig. 4, having apertures 6 intended to permit passage of the bolt therethrough and provided with a keeper 7 of such shape as to support the wires of the bonds and, preferably, to press the same into contact with the fish plate 8. 105

While I may make use of the keeper shown 110

in Figs. 1 to 4 to support merely, forming a loose contact with the bond or bonds or of a keeper for this purpose above such as is shown in Figs. 5, 6 and 7, I prefer to have the keeper make intimate contact with the wires itself and, best of all press the wires tightly against the fish plates for the double reason of better electrical contact therewith both on the part of the keeper and fish plate and because it enables me to grip the bonds firmly at the desired points and keep them stretched taut between these points.

I preferably apply my clip with its keeper to at least two points along the fish plate, having illustrated it as applied in the location of the bolts 9, these being the outside bolts through the fish plate, but it may evidently be applied where desired. The edge 10 may be turned up to conform to the bend in the fish plate and is made use of by me to prevent turning of the clip about the bolt.

I have shown my clip and keeper applied upon the nut side of the bolt in Fig. 2 between the nut lock 11 and the fish plate but may use it as shown in Fig. 3 upon the head side of the bolt between the head 12 and the fish plate upon that side of the rail.

In the form shown in Figs. 5, 6 and 7 I provide my clips 13, 14 and 15 with a keeper in the form of a loop 16 which I have shown as downwardly turned therefrom but which evidently may be otherwise constructed. As I have illustrated it I turn the metal outwardly at 17, downwardly at 18 and inwardly at 19 using preferably the metal upon the lateral edges of my clips for this purpose and thus providing a plurality of such loops 16 for each clip.

40 I have shown the opening in Fig. 5 as made in the form of an inverted U, permitting the clip to be placed over the bolt without taking the nut off or the bolt out. In this form I have shown the ends 20 as approaching more nearly to each other than the portions of the material at the center 21 with the purpose and intent that the opening at 20 shall be slightly less than the diameter of the bolt so that the clip will be sprung 45 slightly when it is put into place and be retained by its resilience against accidental disengagement if the bolt or nut be loosened.

In the form shown in Fig. 6 I have shown an oval opening 22 for the purpose of fitting 55 the elliptical portions of the shanks of the bolts at present in use upon many rail joints.

In Fig. 7 I have shown the usual opening 23 with which form of opening I have also illustrated Fig. 4, it being evident that any 60 required or desired form of opening may be used with either keeper with a large part of the advantage of my invention.

Having thus described my invention what I claim as new and desire to secure by Letters Patent, is:

1. In a device of the character described, a rail bond, a fish plate, a bolt and nut retaining said fish plate and a keeper held in place by the bolt and nut and supporting the rail bond exteriorly of the fish plate. 65

2. In a device of the character described, a pair of meeting rails, a fish plate, a rail bond spanning said fish plate, a keeper supporting said rail bond and means for retaining the fish plate and keeper in place. 70

3. As an article of manufacture, a rail bond support comprising a clip for engagement with the fish plate and its retaining means and a keeper forming a support for a rail bond exteriorly of the fish plate. 75

4. As an article of manufacture, a rail bond support comprising a clip exteriorly supported upon the fish plate and means upon said clip for engagement with the rail bond. 80

5. In a device of the character described an exposed rail bond, means for securing it in place, a clip, a keeper upon said clip and means for supporting the clip and keeper. 85

6. In a device of the character described, a pair of rails, a fish plate uniting them, an exposed rail bond electrically connecting said rails and a clip support for said rail bond applied intermediate the end of the bond. 90

7. As an article of manufacture, a support 95 for an intermediate portion of an exposed rail bond.

8. In a device of the character described, an exposed rail, an exposed bond connected therewith and means for supporting the bond 100 intermediate its points of attachment with the rail and independent of such points of attachment.

9. In a device of the character described, a rail, a fish plate, a bond secured to the rail 105 upon each side of the fish plate, and means for tightly gripping said bond in proximity to but independent of its points of attachment with the rail.

10. In a device of the character described, 110 a rail bond, a fish plate, a clip on said fish plate, an ear on said clip forming an opening for said rail bonds, and means to secure said rail bond to the rail.

11. In a device of the character described, 115 a fish plate, a pair of rails, a rail bond secured thereto and means independent of its points of attachment to the rails for keeping the bond close to the fish plate and exterior thereto.
